UNITED STATES PATENT OFFICE.

RURIC W. JORDAN, OF HOLDERNESS, NEW HAMPSHIRE.

AEROPLANE.

1,369,746.

Specification of Letters Patent. Patented Feb. 22, 1921.

Application filed March 13, 1918. Serial No. 222,205.

To all whom it may concern.

Be it known that I, RURIC W. JORDAN, a citizen of the United States, and resident of Holderness, in the county of Grafton and State of New Hampshire, have invented certain new and useful Improvements in Aeroplanes, of which the following is a specification, reference being had therein to the accompanying drawing.

10 My invention relates to aeroplanes or airships, and more particularly to means for stabilizing the same. The object of the invention is to prevent the many accidents which commonly arise through the falling 15 of an aeroplane or some other uncontrollable action thereof which results when the engine stops during the flight or some contingency occurs which causes the operator to lose control and the aeroplane to fall to the earth. 20 My invention consists essentially in means for automatically controlling the plane whenever the engine stops, or some other accident happens, so that the plane instead of dropping as a dead weight in a vertical line, 25 will be caused to gently glide down an incline, or in other words, to volplane to earth. The means for doing this consists essentially of a weight-carrying frame hung beneath the plane, which will automatically tilt the 30 plane when the propelling action of the motor ceases; and further the invention may be said to consist essentially in the construction, arrangement and combination of the various parts substantially as will be hereinafter described and claimed.

In the accompanying drawing illustrating my invention:

40 Figure 1 is a side elevation of my improved aeroplane when in the position which it occupies when being propelled forward by its motor.

Fig. 2 is a side elevation of the same when in the position which it assumes when the motor or motors have ceased running, and 45 the weight suspended beneath the plane has tilted the latter so that it is in a position to glide toward the earth and thus avoid falling in a vertical descent.

50 Fig. 3 is a front elevation of my improved aeroplane.

Fig. 4 is a top plan view of the same.

Similar characters of reference designate corresponding parts throughout the different figures of the drawing.

55 1 denotes a single plane of that specimen of the invention which I have illustrated

in the drawings, and am now describing. Though I show a monoplane, it is evident that the invention may be applied with equal success to a biplane, triplane, or other aeroplane, or any aerial vehicle. Supported on the plane 1 is a suitable light frame work 2 having a rearward extension 2^a. The frame 2 extends downwardly from the frame 1 for a suitable distance and is designed to carry the 60 weight of a motor, a group of passengers, suitable equipment, machinery, guns, bombs or the like; and the rearwardly extended portion 2^a of said frame is intended or designed to have a rudder 3 pivoted thereto, 65 and to have also the elevating plane or tail 4 hinged thereto, the latter being controlled by suitable connecting means, as 5, or otherwise. It will be understood, of course, that the parts of the frames 2 and 2^a may be made 70 as numerous or as few as desired, and made of any light strong material, and the braces and counterbraces and connecting parts may all be arranged and modified within wide limits, it being only necessary that this 75 frame should occupy a depending position below the plane 1, after the manner of a pendulum, so that it can carry the proper weight, and this weight will be so placed that it will fall directly below the center of 80 the lifting power of the plane when the propelling power is shut off. Above the plane 1 there is a multiple arrangement of guy rods, cables or braces 6 which run from the central top frame 7 above the plane 1 to 85 various points on the plane 1 that are symmetrically placed with relation to each other; while below the plane there is a similar multiple arrangement of wires or cables 8 which run from the lower end of the frame 90 2 to points on the underside of the plane 1 practically opposite to the points where the ends of the guy wires 6 are attached, all as clearly shown in Figs. 3 and 4.

With a plane, as 1, arranged in connection 100 with a depending framework, as 2, I find it most convenient to employ two propellers 9 and 10, the upper one 9 being carried on a shaft 11 which is journaled in the frame 2, near the plane 1; while the propeller 10 has 105 its shaft 12 driven by a motor 13 which is supported in the lower end of the frame 2. In order that the propellers 9 and 10 may run in unison, I couple them together by means of a sprocket chain 14 passing around 110 a sprocket wheel 15 on shaft 11 and another sprocket wheel 16 on the shaft 12. The mo-

tor 13 will, therefore, drive both the upper propeller 9 and the lower propeller 10, and thus drive the aeroplane forward in the direction of the arrow shown in Fig. 1; and 5 when the aeroplane is thus being driven and is normally in its proper position under the action of the two propellers, it will appear as indicated in Fig. 1 and its plane will have the position there shown. Both propellers 10 pull the same load and run at the same speed, but the lower part of the machine will travel faster than the top until it reaches a certain angle beyond which it cannot go since the weight of the car will then begin to pull back 15 directly upon the lower propeller.

Referring to Fig. 2, it will be seen that I have shown there a vertical dotted line a, a , which runs through a point A in the plane 1, which point is the center of lifting 20 power, and also through a point B at the lower end of the frame 2, which point may be called the center of the weight. The angle of the machine shown in Fig. 2 is the angle that it will take when the power of the 25 motor 13 is shut off while the machine is in the air and making a flight. When this happens the center of the weight, as B, will fall in a vertical line directly below the center of the lifting power, as A, along the 30 line a, a , as already explained, thus deflecting the position of the plane 1 so as to bring its front edge C down so that it will be lower than its rear edge D. When this position of the plane 1 takes place, it will begin to 35 fall and it will travel ahead. As it gains in speed in thus falling, the wing resistance against the lifting of the plane 1 will force the plane back and bring the car again into the level position shown in Fig. 1, so that 40 it will travel ahead, and while so moving will fall easily and lightly at the rate of about one foot in fifty feet of forward movement, and will thus effect an easy landing. This it will do without the use of any controls, but if controls are utilized and the 45 rear elevating plane 4 is properly manipulated, the operator, when the machine nears the ground, can lift up the rear of the elevating plane 4 and make the aeroplane cut 50 sharply toward the ground, thus causing the front of the machine to tip up and bring the wings to a sharp lifting angle and thus effecting a light, easy, and satisfactory landing, but as already stated, there is really no 55 need of having controls on the main plane or planes because the weight is far below the plane, and hence the plane will always be kept right side up. It cannot overturn no matter how strong may be the wind or how 60 uncertain the air currents or whatever other disadvantages may happen. Even if half of the plane 1 is shot or broken away, this will simply cause the other half to tilt to an incline, but the aeroplane itself will not 65 be overturned and will volplane or sail.

lightly toward the earth in the same manner that I have already described. When the machine is thus falling, the operator if he wishes, can not only control the movement by the use of the tail 4, but can also steer 70 in the usual manner by means of the rudder 3.

It will thus be seen that by the simple expedient of hanging the weight of the frame, the machinery and the like, below 75 the plane at such a point that when the aeroplane is left free to move about in the air without the action of the propellers, the center of the weight will fall directly below the center of the lifting force and thus tilt 80 the plane so that it will act to glide toward the earth, every needed condition of safety in the management of an aeroplane is secured and assured, as it is impossible that the plane should do otherwise than to sail 85 gradually downwardly and effect an easy and safe landing. The important feature of the invention is to have the center of the weight vertically beneath the center of the plane when there are no other forces acting 90 to keep the plane level, and to have the plane itself so related to the weight that the front edge of the plane will be below its rear edge when the weight hangs vertically below the plane. As already indicated, it 95 is entirely possible that a very wide change in the exact arrangement of the various parts may be made without exceeding the scope of the invention, and I reserve the liberty of making all such changes as may 100 be found to be desirable; for the invention is broad in its essential principles and it is adaptable for a great variety of air craft.

Having thus described my invention, what I claim as new and desire to secure by Letters Patent, is:—

In an aeroplane, stabilizing means therefore, consisting in the combination with a plane, of a frame suspended beneath the same and having a rearward extension, a 110 motor carried by said frame, a propeller in the lower portion of the frame driven by said motor, another propeller in the upper portion of the frame near the plane, gearing from the motor to the second propeller for 115 driving it in unison with the first propeller, the first propeller being set farther forward than the second propeller, all the parts being so arranged that the frame may hang as a pendulum beneath the plane and the plane 120 may be kept in flying position when the motor is in operation but said frame being adapted to drop into a vertical position and shift the angle of the plane when the motor ceases to act, whereby the aeroplane 125 may glide to earth without danger.

In testimony whereof I hereunto affix my signature.

RURIC W. JORDAN.
